Primary Examiner — Clare Ann Gannon(57) **CLAIM**

The ornamental design for a top beam for curtain, as shown and described.

DESCRIPTION

FIG. 1 is a perspective view of a top beam for curtain, showing our new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof;

FIG. 7 is a bottom plan view thereof; and,

FIG. 8 is an enlarged view of FIG. 6.

The break lines shown in FIGS. 1-5 symbolize breaks in the length of the top beam for curtain in which the claimed design is embodied and that the appearance of any portion of the top beam for curtain between the break lines forms no part of the claimed design. All S-shaped curves in evenly broken lines in FIGS. 1-5 form no part of the claimed design.
